UNITED STATES PATENT OFFICE.

PETER ZIMBELMANN, OF AURORA, ILLINOIS.

MAIL-BAG CATCHER.

1,290,003.

Specification of Letters Patent. Patented Dec. 31, 1918.

Application filed December 7, 1916. Serial No. 135,687.

To all whom it may concern:

Be it known that I, PETER ZIMBELMANN, a citizen of the United States, and a resident of the city of Aurora, county of Kane, and 5 State of Illinois, have invented certain new and useful Improvements in Mail-Bag Catchers, of which the following is a specification.

My invention relates to improvements in 10 mail catching devices designed for use upon a mail car to effect catching of a properly suspended mail bag during travel of the mail car.

The object of my invention is the production of a mail catching device, as mentioned, 15 which will be of durable and economical construction, one which may be readily and easily operated, and one which will be highly efficient in use.

20 Other objects will appear hereinafter.

The invention consists in the combinations and arrangement of parts hereinafter described and claimed.

The invention will be best understood by 25 reference to the accompanying drawings forming a part of this specification, and in which,

Figure 1 is a fragmental side elevation of 30 a conventional mail car to which is applied a mail catching device, embodying the invention,

Fig. 2 is a section through the car looking outwardly through the car door, showing the arrangement of the mail catching mechanism therewith, portions of the inner wall of 35 the car being broken away to expose underlying parts,

Fig. 3 is an end view of the mail car illustrating the method of suspension of a mail 40 bag and the engagement thereof by the mail catching device, when the device is in use,

Fig. 4 is a section taken on substantially line $x-x$ of Fig. 2,

Fig. 5 is a view similar to Fig. 4 except 45 that the device is here shown in folded or inoperative position,

Fig. 6 is a detail section taken on line $y-y$ of Fig. 1, and

Fig. 7 is a detail section taken on line $z-z$ 50 of Fig. 2.

The preferred form of construction as illustrated in the drawings is designed for use in connection with a mail car which is shown at 1, said car having a side door opening 2, as is usual.

The mail bag catching device which is de-

signed for use in connection with said car comprises a vertically extending shaft 3 which is arranged upon the outer side of the car, the same being rockingly mounted in 60 suitable bearings 4. Fixed to and projecting from the shaft 3 are two spaced arms 5 which are connected at their outer ends by a vertically extending bar 6. Pivotedly connected with the ends of bar 6 are two elongated bars or links 7 which are spaced apart and connected together at their front ends by a bar 8. Intermediate the ends of links 7 is provided a bar 9 which is pivotally connected by means of a plurality of spaced parallel links 10 with a vertically extending shaft 11, the ends of which are mounted in suitable bearings 12 which are arranged at one edge of the door opening 2. The bars 8 and 9 are also connected by links 7' which 70 are spaced between the links 7, extending parallel therewith, as clearly shown in Fig. 1. The various links or arms connected with the various bars or shafts are held in spaced relation by means of sleeves 13 arranged 75 upon the former, said sleeves being of proper lengths to perform the function mentioned, as clearly seen in Fig. 1. Said sleeves are also loosely mounted so that when the mail bag which is caught by the device is brought 80 in contact therewith, said sleeves will be adapted to rotate and thus serve as rollers to reduce friction, as will be readily understood.

The arrangement is such, as will be seen, 90 that a foldable frame is formed which is adapted to assume a laterally projecting unfolded or operative position, as shown in Fig. 4, or a retracted or folded inoperative position, as shown in Fig. 5. In the latter 95 position said frame is adapted to assume a position in close proximity with the side of the car so as to avoid any danger of contact of the outer end thereof with any obstacle. In order to permit of folding of links 7 to 100 the position shown, said links are formed at their inner edges with recesses 14 which afford clearance for the shaft 3 when the frame is folded as shown in Fig. 5. When said frame is in unfolded or operative position, 105 the front end thereof projects laterally from the car to such an extent, that in the travel of the car, said end of the frame will be adapted to engage with a properly suspended mail bag, the links 7 and 7' and links 110 10 forming an inclined slide or deflector adapted to deflect the bag thus engaged in

wardly through the door 2 into the interior of the car, as will be readily understood. As seen in Fig. 4 the links 7 and 7' are inclined but slightly so as to reduce the jar upon the 5 bag to a minimum, the links 10 being further inclined to secure the desired deflecting action.

In the movement of the frame to unfolded or operative condition, the joint between the 10 rearward ends of links 7 and the outer ends of arms 5 passes beyond the dead center and said arms rest against the side of the car which serves as a stop therefor. With this arrangement any pressure on the frame resulting 15 from engagement with a mail bag will serve simply to press the rearward ends of links 7 and the outer ends of arms 5 into closer engagement with the side of the car, thus precluding folding of the frame 20 when in use.

Actuation of the catching frame described is effected by means of a bevel gear 15 which is provided at the lower end of shaft 3, said gear meshing with a bevel gear 16 which is 25 provided at the outer end of a transversely extending shaft 17 mounted in the outer wall of the car body as seen in Fig. 6. The inner end of shaft 17 is provided with a bevel gear 18 which meshes with a bevel gear 19 30 provided at the lower end of a vertically extending shaft 20 which is mounted in suitable bearings provided between the inner and outer walls of the car. At the upper end of shaft 20 is provided a bevel gear 21, 35 as seen in Fig. 2, which gear meshes with a bevel gear 22 provided at one end of a shaft 23, the latter being mounted in suitable bearings also arranged between the inner and outer walls of the body of the car. Coöperating 40 with shaft 23 is a helical torsional spring 24 which is adapted, normally, to hold the mail bag catching frame in folded or inoperative condition.

Provided at one end of the shaft 23 is a 45 handle or arm 25 which, when the mail bag catching frame is in folded or inoperative condition, extends upwardly in a vertical plane as shown in dotted lines in Fig. 2. The arrangement is such that, in order to unfold 50 the frame to operative condition, said handle or arm 25 needs only to be rocked downwardly to the full line position, as shown in Fig. 2. When this is done said handle, through the medium of the shafts and gears 55 described, effects rocking of the shaft 3 with the result of moving forward and hence unfolding the frame to the condition shown in Fig. 4. Said frame is releasably locked in unfolded or operative condition by means of 60 a bolt 26 of a suitable conventional spring lock 27 which bolt is adapted for engagement with a lateral projection 26' provided upon the arm 25, as clearly seen in Fig. 7. The bolt 26 is slidably mounted, the same 65 being normally held at its outer terminal of

movement as shown in Figs. 2 and 7, in which position the same is adapted to hold the arm 25 in its lowered position. Said bolt, however, only yieldingly holds said arm, the outer end of said bolt at the place of engagement therewith of said arm being beveled, as seen in Fig. 7, so that when sufficient inward force or pressure is applied to said arm, said bolt will yield or retract and thus release said arm. Provided upon 75 said arm is a projection 28 which, when said arm is in lowered position, projects into the door opening 2 into the path of the mail bag which is deflected by the mechanism, before described, through said door opening. The arrangement is such that, when a bag is engaged by the mechanism and delivered into the car in the manner above described, said bag will strike the projection 28 on arm 25 as the bag passes through the door, the force 80 of the blow on said arm being sufficient to cause bolt 26 to yield or retract so as to release the arm 25 from said lock bolt 26 and permit of the mail bag catching frame being moved to folded condition under the influence of spring 24.

The inner wall of the car body is cut away as at 29 in order to afford clearance for the arm 25 and lock 27, as clearly seen in Fig. 2.

In the operation of the mechanism then, 95 it will be seen that the mail bag indicated at 30 in Fig. 3 and which is suitably suspended along the track by a suitable suspending element 31 will, as the train passes, and with the catching mechanism in unfolded or operative position, engage with the bag, and remove the same from element 31 and deflect said bag inwardly into the interior of the car through the side door thereof. As the bag passes into the car its own movement or 100 momentum will be utilized to release the engaging mechanism which will be automatically folded to inoperative position under the influence of spring 24.

The lower end of the mail bag catching frame may be provided with a suitable suspending element 32 for the suspension of a mail bag 33 which it is desired to deliver to a stationary mail bag catching mechanism arranged along the track so that, with this 115 arrangement, a mail bag may be received from a station and another delivered to the station at the same time. The mail bag catching mechanism of the receiving station must, of course, be positioned in a plane below that of the catching mechanism arranged upon the mail car so that there will be no interference between the two.

While I have illustrated and described the 125 preferred form of construction for carrying my invention into effect, this is capable of variation and modification without departing from the spirit of the invention. I, therefore, do not wish to be limited to the precise details of construction set forth, but 130

desire to avail myself of such variations and modifications as come within the scope of the appended claims.

Having described my invention what I claim as new and desire to secure by Letters Patent is:

1. The combination with a car having a side opening, of an engaging element foldably mounted on the car adjacent said opening and adapted, during travel of the car and when said element is unfolded to engage a properly suspended mail bag and deflect the same into the interior of the car through said opening, said element comprising a main engaging element; a supplemental engaging member pivotally connected at one end with the car and having its opposite end pivotally connected with said main engaging member intermediate the ends of the latter; an oscillatory shaft; and an arm on said shaft pivotally connected with the rearward end of said main engaging member adapted, upon oscillation of said shaft, to effect folding or unfolding of said element, said arm in the folding of said element from folded to unfolded position moving past dead center, substantially as described.
2. The combination with a car having a side opening of an engaging element foldably mounted on the car adjacent said opening, and adapted, during travel of the car and when said element is unfolded, to engage a properly suspended mail bag and deflect the same into the interior of the car through said opening, said element comprising a main engaging member; a supplemental engaging member pivotally connected at one end with the car and having its opposite end pivotally connected with said main engaging member intermediate the ends of the latter; an oscillatory shaft; and an arm on said shaft having an amplitude of oscillation of substantially 180° about a vertical axis, said arm being pivotally connected with the rearward end of said main engaging member and being adapted, when rocked forwardly to its forward terminal of movement, to shift said engaging members forwardly and outwardly to operative position, and when rocked rearwardly to its rearward terminal of movement to shift said engaging members rearwardly and inwardly to folded position against the side of the car, substantially as described.

ing member, adapted, when rocked forwardly to its forward terminal of movement, to shift said engaging members forwardly and outwardly to operative position, and when rocked rearwardly to its rearward terminal of movement, to shift said engaging members rearwardly and inwardly to folded positions against the side of the car, substantially as described. 45

3. The combination with a car having a side opening of an engaging element foldably mounted on the car adjacent said opening and adapted, during travel of the car and when said element is unfolded, to engage a properly suspended mail bag and deflect the same into the interior of the car 55 through said opening, said element comprising a main engaging member; a supplemental engaging member pivotally connected at one end with the car and having its opposite end pivotally connected with said main 60 engaging member intermediate the ends of the latter; an oscillatory shaft; and an arm on said shaft having an amplitude of oscillation of substantially 180° about a vertical axis, said arm being pivotally connected 65 with the rearward end of said main engaging member and being adapted, when rocked forwardly to its forward terminal of movement, to shift said engaging members forwardly and outwardly to operative position, and when rocked rearwardly to its 70 rearward terminal of movement to shift said engaging members rearwardly and inwardly to folded position against the side of the car, substantially as described. 75

In testimony whereof I have signed my name to this specification in the presence of two subscribing witnesses.
